UNITED STATES PATENT OFFICE.

ARTHUR E. SMALL, OF OAK PARK, ILLINOIS, ASSIGNOR TO UNION METAL PRODUCTS COMPANY, OF CHICAGO, ILLINOIS, A CORPORATION OF DELAWARE.

DEVICE FOR OPERATING CAR COUPLERS.

Original application filed October 8, 1924, Serial No. 742,395. Divided and this application filed March 9, 1925. Serial No. 14,282.

This particular invention relates to what is generally known in the art as a rotating type of uncoupling device for car couplers and comprises an operating rod revolvably mounted on the car with brackets or in any other convenient manner, which rod is usually bent downwardly at the outer end to form a handle, and is bent outwardly at its inner end to form a crank projecting over the coupler lock lifter. The standard vertical plane coupler has a knuckle pivoted to the coupler head and provided with a tail behind which the lock is placed. The lock lifter protrudes through and above the coupler head and is provided with a horizontally positioned eye. This lock lifter eye is $1\frac{1}{16}$ " in diameter and its axis is perpendicular to the longitudinal center of the car. This size and position has been determined by the American Railroad Association and is standard for the majority of couplers now in service.

My invention resides in the connection between the crank of the operating rod and the eye on the coupler lock lifter. When the handle is raised the rod is revolved and the crank is thereby raised which unlocks the coupler by raising the lock lifter.

The coupler moves backwardly and forwardly longitudinally of the car in buffing and draft and also moves sidewise in rounding curves, etc., and the connection between the coupler and the operating rod must permit such movements without the component parts becoming disengaged from each other or from either the coupler or the operating rod. It is frequently necessary to uncouple cars when they are coupled together and in contact so that it is impossible to throw the knuckle of either coupler. To meet this condition couplers are designed to assume a "lock set position" wherein the lock lifter can be raised from behind the tail of the knuckle and retained in such a position by means within the head of the coupler independent of the operating rod. This allows the operating rod to fall close to the lock lifter. To accommodate such a movement the connection between the operating rod crank and the coupler must fore-shorten or have a sliding engagement with either the operating rod or the coupler.

Another object is to provide a connection which may be hooked into the eye of the

coupler lock lifter with the hooked member connected to the crank of the operating rod by another member which permits it to adapt itself to the various service movements of the coupler but prevents it from becoming disengaged from the lock lifter in service.

In the drawings:

Fig. 1 shows a portion of a railway car with my invention applied thereon.

Figs. 2 and 3 show an enlarged assembly of my device.

In a railway car the coupler operating rod 1 is mounted on the end sill 2 by brackets 3 and has a handle 4 at its outer end and a crank arm 5 extending over the coupler. The lock lifter 7 of the coupler 8 has a horizontally disposed eye 9. My invention resides in a connector for the crank arm to the lock lifter.

There are two open hooks 60-61 (preferably duplicates) which engage an eye 62 of the operating rod crank arm 5 and the lock lifter eye 9 respectively. The bars 63-64 are preferably flexibly connected together and are threaded or screwed into the tapped arms of the hooks (60-61) and project therethrough far enough to substantially close the open portion 65-66 of the hooks.

One of the bars may have a right handed thread 67 for engagement with the hook (60) while the other bar may have a left handed engagement (68) with the other hook (61) so that when the two bars are rotated in unison both bars simultaneously move so as to open (or close) the open portions of both hooks. Engagement and disengagement of the device to the operating rod 1 and coupler 8 are very simple performances. A locking lip 69 is provided on either hook (or both if desired) which is moved to the position shown in full lines, after the device is assembled, to prevent the rotation of the bars. Thus the component parts are held in proper relative relation. Shoulders 70 may be provided on the bars to restrict their longitudinal movement.

This is a division of my co-pending application, Serial No. 742,395, filed October 8, 1924.

I claim:

1. A connector for a car coupler lock and its operating rod comprising two open hooks and two bars flexibly connected together,

each bar closing the open portion of one of said hooks and having a threaded engagement therewith.

2. A connector for a car coupler lock and its operating rod comprising two open hooks, two bars flexibly connected together, each bar closing the open portion of one of said hooks and having a threaded engagement therewith, and means to prevent the rotation of one of said bars relative to its adjacent hook.

3. A connector for a car coupler lock and its operating rod comprising two open hooks, two bars flexibly connected together, each bar closing the open portion of one of said hooks and having a threaded engagement therewith, and means integral with one hook to prevent the rotation of its adjacent hook.

4. In a device for operating the lock of a car coupler, the combination of a coupler operating rod having an eye, a coupler lock lifter having an eye, two open hooks, each engaging one of said eyes, and two bars flexibly connected together, each bar closing the open portion of one of said hooks and having a threaded engagement therewith.

5. In a device for operating the lock of a car coupler, the combination of a coupler operating rod having an eye, a coupler lock lifter having an eye, two open hooks, each engaging one of said eyes, two bars flexibly connected together, each bar closing the open portion of one of said hooks and having a threaded engagement therewith, and

means integral with one hook to prevent the 35 rotation of its adjacent bar.

6. In a device for operating the lock of a car coupler, the combination of a coupler operating rod having an eye, a coupler lock lifter having an eye, two open hooks, each 40 engaging one of said eyes, two bars flexibly connected together, each bar closing the open portion of one of said hooks and having a threaded engagement therewith, and means to prevent the rotation of one of said 45 bars relative to its adjacent hook.

7. In a device for operating the lock of a car coupler, the combination of a coupler operating rod having an eye, a coupler lock lifter having an eye, two open hooks, each 50 engaging one of said eyes, and two bars flexibly connected together which close the open portion of said hooks respectively, one of said bars having a right hand threaded engagement with one hook and the other 55 bar having a left hand threaded engagement with the other hook.

8. In a device for operating a car coupler, the combination of a coupler operating rod having an eye, a coupler lock lifter having an eye, two open circular hooks, each engaging one of said eyes, and two bars flexibly connected together, each bar closing the open portion of one of said hooks and having a threaded engagement therewith, the 65 centers of said hooks being in line with the longitudinal axes of said bars.

ARTHUR E. SMALL.
